(57) **CLAIM**

The ornamental design for a cube-shaped playset, as shown and described.

DESCRIPTION

FIG. 1 is a front perspective view of a cube-shaped playset showing side panels of the playset in a closed position according to our new design;

FIG. 2 is a front perspective view of the cube-shaped playset of FIG. 1 with a lower drawer in an open position;

FIG. 3 is a top plan view of the cube-shaped playset of FIG. 1;

FIG. 4 is a bottom plan view of the cube-shaped playset of FIG. 1;

FIG. 5 is a back plan view of the cube-shaped playset of FIG. 1;

FIG. 6 is a top plan view of the cube-shaped playset showing all four side panels with accompanying extensions in an open position;

FIG. 7 is a bottom plan view of the cube-shaped playset showing all four side panels with accompanying extensions in an open position; and,

FIG. 8 is a side perspective view of the cube-shaped playset showing the front panel in an open position with its accompanying extension, as well as rotatable stabilizers extended down.

The broken lines are for the purpose of illustrating portions of the article that form no part of the claimed design.
